SEWING MACHINE

Booker W. Davidson, Michigan City, Ind.

Application September 9, 1937, Serial No. 163,129

6 Claims. (Cl. 112—201)

My invention relates to improvements in sewing machines of the so-called chain-stitch type.

The primary object of my invention is to equip a double thread machine for the formation of a reinforced chain stitch, and with improved loop forming and manipulating mechanism.

Another object is to provide an improved thread supply for such machines together with efficient guiding and tensioning means for the lower thread.

Other and subordinate objects are also comprehended by my invention, all of which together with the exact nature of my improvements, will be readily understood when the following description and claims are read with reference to the accompanying drawings.

In said drawings:

Figure 1 is a view partly in side elevation and partly in section of a sewing machine embodying my improvements.

Figure 2 is a view in perspective of my improved guiding and tensioning means for the lower thread and a rotary hook or loop taker associated therewith.

Figure 3 is a view in perspective of the thread guiding and tensioning means and loop taker illustrating operation of the latter.

Figure 4 is a perspective view of a loop pick up mechanism.

Figure 5 is a perspective view illustrating the formation of the stitch, and

Figure 6 is a side elevation of a threading hook.

Referring to the illustrated embodiment of my invention in detail, with reference thereto by numerals, 1 designates the usual bed plate of the Singer sewing machine of commerce, 2 the standard thereof, 3 the tubular arm, 4 the head, and 5 the balance wheel. Associated with the head 5 is the usual thread take-up lever 6, tensioning disks 7 for the upper thread, thread guides 8 and 8', presser foot 9, and needle bar 10, driving the needle 11 through the usual throat plate 12. The driving mechanism, being well understood in the art, has not been illustrated, with the exception of the drive shaft 13, the jack shaft 13' the bevel gear drive 14 between said shafts and the bevel gear 14' on the jack shaft 13' all of which form part of the usual drive for the rotary hook or loop taker of the well known Singer lock stitch sewing machine of commerce as exemplified in U. S. Patent No. 1,105,968 to which attention is directed for a more complete disclosure of the driving mechanism.

According to my invention, the usual rotary hook or loop taker 15 is affixed to the forward end

of a tubular operating shaft 16 therefor journaled in front and rear bearing sleeves 17, 17' mounted in front and rear bearings 18, 18' depending from the bed plate 1. The tubular operating shaft 16 extends beneath and slightly beyond the before-mentioned bevel gear 14' into a housing 19 suitably secured to the under side of the bed plate 1 and to the rear bearing 18'. A bevel gear 16' fast on said tubular shaft 16 meshes with the bevel gear 14' whereby said shaft 16 is driven as will be clear. The ratio of drive between the rotary hook or loop taker 15 and the needle bar 10 is one revolution of the former to one reciprocation of the latter.

Suitably mounted in the rotary hook or loop taker 15, in substantially the same relation thereto as the usual bobbin casing of the above designated machine, is a combined guide and tensioning device 20 for the lower thread comprising a cylindrical casing 21 having open front and rear sides with the exception of a transverse central bar 22 extending across its rear side thereof. The casing 21 is located directly beneath the needle 11 and has a needle clearance opening 23 therein for a purpose presently seen. Secured to the cross-bar 22 and within the casing 21 is a thread guiding nipple 24 of tapered form having its rear end aligned with the tubular shaft 16. The nipple 24 inclines upwardly and rearwardly and terminates adjacent to a resilient thread tensioning member 25 clamped to the front edge 26 of the casing 21 by a screw 27. The casing 21 is removably secured in the rotary hook or loop taker 15 by suitable means (not shown) and slightly spaced from the latter to provide a slight clearance therebetween so that the rotary hook or loop taker 15 is freely rotatable around said casing 21. A latch member 28 mounted on a fixed part of the machine cooperates with a notch 29 in the front edge 26 of the casing 21 to hold the combined guide and tensioning device 20 stationary. The front edge 26 of the casing 21 inclines downwardly and rearwardly so that the loop taker 15 will extend forwardly beyond said edge 26 of the casing 21 at the bottom of the latter for a purpose presently seen.

Suitably mounted upon a fixed support 30 at the balance wheel end of the machine is a pair of thread spindles 31 and 32 for the lower and upper threads, respectively, and rotatably mounted, in any suitable manner, on said support 30. A pair of thread guides 33 extend upwardly from said support 30 in overlying relation to the spindles 31 and 32. A tubular arcuate thread guide 34 is suitably secured at one end to the support 30

30 to extend to an opening 35 in the rear wall of the housing 18 in axially alignment with the tubular drive shaft 16. Intermediate the spindles 31 and 32 and mounted on the support 30 is a pair 5 of thread tensioning disks 36. The tensioning disks 36 are relatively adjustable to impose a variable tension upon the thread and by means of a knurled thumb nut 37 and a tension spring 38.

The upper thread 39 is led from the spindle 10 32 through one of the thread guides 33, to suitable thread guides 40 on the arm 3 and then in the usual manner around the tensioning disks 7, through the thread take-up lever 6 and the thread guides 8 and 8' to the needle 11. The lower 15 thread 41 is led from the spindle 31 over and between the tensioning disks 36, through the tubular thread guide 34, opening 35, tubular shaft 16, and nipple 24. From the nipple 24 said lower 20 thread 41 is led beneath the thread tensioning member 25 as shown in Figure 2 and in the initial threading of the machine up through the throat plate 12 in the usual manner.

The operation of the machine as so far described is as follows:

25 When the needle 11 descends a slack is created in the upper thread 39 by operation of the thread take-up lever 6 so that a loop 42 may be formed in the lower end of the upper thread all as is usual and well understood in the art. The loop 30 42 is picked up by the usual hook or beak 15' of the loop taker 15, in the usual manner, and carried part way around the thread guide and tensioning device 21. As best shown in Figure 3, the loop 42 is taken around the front edge 26 of the 35 combined thread guide and tensioning device 20, that is to say, in front of the latter, and over the lower thread 41, until the hook 15' is in its lowermost position and said loop substantially vertical.

At this point the loop 42 is picked off the hook 40 15' and carried up to a position subjacent the needle 11 so that upon the next down stroke of the needle the latter will enter the loop to form a chain stitch. This operation is effected by pick up mechanism now to be described.

45 The basic element of the loop pick up mechanism (Figures 1 and 4) is an eccentric link motion 43 contained, for the greater part, in a housing 44 located beneath the throat plate 12 in advance of the combined thread guide and tensioning device 20. Said motion 43 comprises an eccentric 45 fast on a shaft 46 journaled, at a right angle to the shaft 16, in bearings, as at 47, extending from the front wall of the housing 44, an eccentric strap 48, and a rod 49 integral with said 55 strap and extending therefrom toward said tensioning device 20. The free end of the rod 49 extends through a guide slot 50 in a guide bar 51, in said housing 44, whereby when the shaft 46 is rotated the rod 49 is reciprocated toward 60 and from said tensioning device 20 and at the same time oscillated vertically. Pivoted, as at 52, on the free end of the rod 49 for vertical swinging movement thereon and to be reciprocated thereby is a pick up link, or bar, 53 extending 65 toward the tensioning device 20 and terminating at its free end in a down turned snatch hook 54, pivoted thereon, as at 55, for lateral swinging movement and tensioned against such movement by a leaf spring 56 suitably secured 70 to said link 53, as at 57, and having a slot and pin connection 58 with said hook 54. The link 53 is guided in its movement by a pair of vertically slotted guide bars 59 and 60 upstanding from the bottom of the housing 44. A suitable 75 spring 61 secured in the slot 60 of one bar 60

and loosely bearing against the link 53 tensions the latter against upward movement. Cooperating with the pick up link 53 is a cam 62 rotatably mounted on the guide bar 60 subjacent said link and adapted during each revolution to cam said link upwardly, against the tension of the spring 61, on the pivot 52 so that the snatch hook 54 is located above the level of the top of the loop taker 15 as shown in dotted lines in Figure 1. Cooperating with the snatch hook 54 to cam the 10 same laterally is a cam lug 63 upstanding from the bottom of the casing 21 on the inner face thereof and for a purpose presently seen.

In the before described position to which the loop 42 is carried by the loop taker 15 at which 15 point in the machine operation the needle 11 is nearing the limit of its upstroke position, the position of the described parts of the loop pick up mechanism is as follows. The pick up link 53 is in the limit of its down stroke position and 20 slightly in advance of the cam 62 and loop taker hook 15'. The eccentric 45 is positioned to impart a slight forward thrust to said link 53 upon initial rotation thereof, and the cam 62 is in position to elevate said link 53 following upon said 25 forward thrust. This position of the parts is clearly illustrated in Figures 1, 3 and 4. The eccentric 45 and cam 62 are driven by the following drive mechanism. Suitably journaled in the bearings 18, 18' to extend at its front and rear ends 30 into the housings 44 and 19 is a driven shaft 64. The shaft 64 is driven by means of a jack shaft 65 suitably journaled in the bed plate 1 and arm 3 along side the jack shaft 13' with one end geared to the drive shaft 13 by beveled gearing 66 and 35 its other end similarly connected to the shaft 64 by gearing 67. The other end of the shaft 64 is operatively connected to the shaft 46 by beveled gearing 68 and to the cam 62 by a pair 40 of gear pinions 69 and 70 fast on the shaft 64 and cam 62 respectively. The described drive to the shaft 46 is so arranged and timed that during approximately the last half revolution of the loop taker 15 the eccentric 45 makes a complete 45 revolution and the cam 62 a half revolution.

The operation as regards the loop taker has already been described. It remains now to describe the operation of the loop pick up mechanism.

At the described point in the operation of the loop taker 15 that is in half cycle position thereof 50 and with the loop 42 in vertical position as shown in Figure 3 the eccentric 45 is rotated from the position shown in Figures 1 and 4 to impart a slight forward thrust to the pick up link 53 which thereby enters the snatch hook 54 in said loop 55 and thrusts said hook against the cam 63 whereby said hook is cammed laterally ahead of the beak 15' and the loop 42 snatched off said beak 15'. The link 53 and snatch hook 54 are now retracted during which operation the cam 62 60 raises said link upwardly to the before described elevated position thereof, the eccentric describing substantially a half revolution. The eccentric now executes substantially another half revolution and thrusts the snatch hook 54 with the loop 65 42 thereon below the needle 11 it being understood that said needle is sufficiently elevated for this purpose. During this manipulation of the loop 42 by the link 53 and snatch hook 54 the loop is continuously shortened by the usual tensioning operation exerted by the thread take up lever 6. Substantially coincidentally with location of the loop 42 beneath the needle 11 the latter descends into said loop. At this point the eccentric 45 begins a second revolution retract- 70 75 75

ing the snatch hook 54 and the eccentric 62 releases the link 53. At the end of the second revolution of said eccentric, which occurs during substantially the first half cycle of revolution of the 5 loop taker 15 and formation and positioning of another loop 42 in the manner previously described, the link 53 and snatch hook 54 have been retracted and advanced and lowered by the spring 61 to the starting position previously indicated.

10 In the positioning of the loop 42 beneath the needle 11 the usual chain stitch is formed as will be obvious. However, as an incident to such positioning of the loop 42 each loop is wrapped around the lower thread 41, or vice versa, so that 15 on one side of the material stitched the lower thread is wound around the loops of the chain as shown in Figure 5. Because of the tension effected through the medium of the tensioning member 25 the chain is pulled tighter by the lower thread 41 than in the usual machines and reinforced on one side of the material by said lower thread. The lower thread 41 may be distinctively colored for ornamental purposes or for identifying the one side of the fabric.

20 The lower thread 41 may be inserted through the tubular thread guide 34, tubular shaft 16 and nipple 24 by means of a threading hook 72 of flexible metal inserted through the parts mentioned in a manner which will be understood.

25 The foregoing will, it is believed, suffice to impart a clear understanding of the invention but it is to be understood that the present disclosure is illustrative rather than restrictive and that changes in form and relation of parts described 30 may be resorted to falling within the scope of the protection prayed.

What I claim is:

1. In a sewing machine, the combination with 40 a reciprocating needle and a source of thread supply for said needle, of a rotary loop taker below said needle operative to engage the thread and form a loop therein, and loop pick up mechanism operative to free the loop from engagement with said loop taker and to carry said loop into a position intermediate said needle and loop taker.

2. In a sewing machine, the combination with 45 a reciprocating needle and a source of thread supply for said needle, of a rotary loop taker below said needle operative to engage the thread and form a loop therein, and loop pick up mechanism operative to free the loop from engagement with said loop taker and to carry said loop into a position intermediate said needle and loop taker and including a hook member mounted for vertical swinging and reciprocating movement, and means for moving said hook member.

3. In a sewing machine, the combination with 50 a reciprocating needle, and a source of thread supply for said needle, of a rotary loop taker below said needle operative to engage the thread

and form a loop therein, and loop pick up mechanism operative to free the loop from engagement with said loop taker and to carry said loop into a position intermediate said needle and loop taker, and including a pick up bar mounted for 5 vertical swinging and reciprocating movement, a snatch hook on said bar swingable thereon, means for moving said bar, and means to swing said hook comprising a stationary cam engaged by said hook as an incident to movement of said 10 bar in one direction.

4. In a sewing machine, the combination with a reciprocating needle of a rotary loop taker mounted below said needle and having an axial opening therein, a combined thread guide and 15 tensioning device comprising a cylindrical casing stationarily mounted adjacent to said loop taker axially of the latter, a tubular thread guide in said casing axially aligned at one end with the opening in said loop taker, a thread tensioning 20 member on the outside of said casing to which the thread extends from said guide, a thread supply from which the thread extends through said opening and thread guide, and means for rotating said loop taker.

5. In a sewing machine, the combination with a reciprocating needle, of loop forming mechanism comprising a tubular shaft rotatably mounted below said needle, a rotary loop taker fixed on one end of said shaft adjacent said needle, 30 a combined thread guide and tensioning device including a cylindrical casing stationarily mounted adjacent to said loop taker axially of the latter, a thread guiding nipple fixed in said casing with one end thereof disposed axially of said casing, 35 a thread tensioning member on the outer face of said casing to which the thread extends from said nipple, a thread supply from which the thread extends through said shaft, looper and nipple, and means for rotating said shaft.

6. In a sewing machine, the combination with a reciprocating needle, of loop forming mechanism comprising a tubular shaft rotatably mounted below said needle, a rotary loop taker fixed on one end of said shaft adjacent said needle, a 40 combined thread guide and tensioning device including a cylindrical casing stationarily mounted adjacent to said loop taker axially of the latter, a thread guiding nipple fixed in said casing with one end thereof disposed axially of said casing, 45 a thread tensioning member on the outer face of said casing to which the thread extends from said nipple, a drive for said shaft including gearing, a housing for said gearing into which said shaft extends, a tubular thread guide extending 50 into said housing into axial alignment with said shaft, and a thread supply from which the thread is led to said tubular guide, shaft, and loop taker into said nipple.

BOOKER W. DAVIDSON. 60
